UNITED STATES PATENT OFFICE.

JOSEPH P. DAVIS, OF NEW YORK, N. Y.

TELEPHONE-EXCHANGE SYSTEM.

SPECIFICATION forming part of Letters Patent No. 331,186, dated November 24, 1885.

Application filed May 12, 1885. Serial No. 165,197. (No model.)

To all whom it may concern:

Be it known that I, JOSEPH P. DAVIS, of the city, county, and State of New York, a citizen of the United States of America, have 5 made a new and useful Improvement in Telephone-Exchange Systems, of which the following is a specification.

In a telephone-exchange system of the general class to which my improvement relates 10 one class of attendants, whom I designate as "annunciator-attendants," have nothing whatever to do but to receive the calls of the subscribers and indicate upon paper strips the connections required. A second class of attendants, herein designated as "operators, trunk and local operators," receive directions from the annunciator attendants of connections to be made between subscribers. A third class of attendants, known as "switchmen," are 15 employed, whose sole duty it is to make switch-connections as directed by the operators. An operator, upon receiving a card from the annunciator-attendant, immediately calls to the particular switchman having facilities for making 20 the particular switch-board connections required, and thereafter said operator makes other connections which complete the operation of placing two subscribers in communication with each other. In other exchanges 25 of this class a horizontal bar, or a pair of such bars extending the entire length of the switch-board, have been employed for each subscriber's line. Usually these long horizontal bars have heretofore been placed one above 30 another upon the vertical face of the switch-board, and thus the number of subscribers' lines that could be connected to the switch-board of an exchange was limited to the comparatively few horizontal strips which could 35 be thus arranged upon the face of said switch-board.

I have found that more than about one hundred horizontal bars, placed one above another, make a switch-board whose upper portion is beyond the reach of the switchmen, and that from this fact, where many subscribers' lines enter a single exchange, it becomes necessary to employ two or more independent switch-boards. With the old form of switch-board several switchmen are employed to make 45 connections without reference to the apportionment of the work. Thus any two of the

subscribers' lines may be connected by any one of the several switchmen—that is, they may be connected first by one switchman, then 55 by a second, and next by a third.

To avoid the possibility of confusion and interference, which would be likely to occur where many switchmen are jointly employed in front of a single switch-board, and to also 60 avoid the necessity for building the switch-boards of inconvenient height, I have provided my improved exchange with a series of sectional switch-boards, to each of which an attendant is assigned. In this species of an 65 exchange there are two classes of operators. There are local operators whose duty it is to make connection between any two subscribers whose lines both come into the same exchange, and there are trunk-line operators who are 70 employed to connect two subscribers whose lines enter different exchanges. Trunk-operators join subscribers through a trunk line joining two central exchanges. That part of the switch-board to which one operator is assigned is known as a "sectional switch-board," and said sectional switch-board is 75 divided into a series of sub-sections, there being as many sub-sections upon each sectional board as there are table operators in 80 the exchange. Each trunk-operator's table is provided, say, with twenty lines, which extend, respectively, to the twenty sockets of a sub-section of the switch-board. Each socket of a sub-section on one sectional board 85 is electrically connected with the corresponding sockets of the same sub-section on the other sectional board. By this arrangement each trunk-operator has twenty lines from his table connecting with every sectional switch-board in the exchange. There are likewise 90 as many sub-sections of switch-plug sockets on each sectional switch-board as there are local operators, and the socket of one sectional switch-board is electrically connected with a 95 corresponding socket of every other board. Each local operator is provided with, say, twenty-five pairs of lines, which respectively connect with the twenty-five pairs of switch-plug sockets of a sub-section of the switch-board. The switchmen have no means of communicating with subscribers, and they are not 100 therefore charged with the duty of conversing with subscribers, but are only charged with the

work of making switch-board connections. The only persons with whom the switchmen have means of communication are the operators, and from these they can receive oral communications, but the switchmen can transmit none in return.

One feature of my invention consists in providing each switchman with a head-telephone which is placed in a local circuit extending 10 to the table of every operator in the exchange, and said local circuit is provided with a spring-jack at each operator's table. Thus an operator can insert his telephonic transmitter in a switchman's line and orally give the necessary directions for connecting the various 15 subscribers' lines at the switch-board. Each switchman has an independent local circuit, including a spring-jack, at each operator's table, and each operator is provided with as 20 many such circuits and spring-jacks as there are switchmen. By this arrangement any one of twenty or more operators may call any one of half a dozen or more switchmen, and any 25 switchman may make certain electrical connections in the process of joining any two subscribers who connect with the exchange. A convenient number of subscribers' lines—say two hundred and fifty—pass through each of the series of sectional switch-boards in the 30 same exchange, and thence to an annunciator-board and to earth. Normally the lines passing through one sectional switch-board are not connected with the other sectional switch-boards. Each subscriber's line enters its 35 switch-board through an electrical cord and a switch-plug which normally rests upon an electrical contact joining the annunciator and earth, and upon lifting the switch-plug the connection through the annunciator-board is 40 broken. In response to calls from the operators a switchman removes any one of the main-line switch-plugs and places it in a socket in the upper part of the switch-board, and thus 45 establishes an electrical connection between a subscriber and the operator's table.

To join any two subscribers' lines coming to the same sectional switch-board, the plugs forming parts of said lines are placed in the respective metallic sockets of any pair upon 50 the sectional board. The movement of a switch at the local operator's table then completes a connection between the two subscribers. To join two subscribers whose lines are connected to different sectional switch-boards in the same exchange, the switchman 55 at one board through which the subscriber's line enters places the switch-plug of said line in a metallic socket, as does the switchman of the sectional board to which the second line is 60 connected. Each socket on one sectional board being connected with a corresponding socket in each of the others, connection is then made between the two subscribers' lines at an operator's table, the same as though the 65 switch-plugs of the two lines were placed in a pair of sockets upon one board. From the trunk-operators' tables trunk-lines extend to

distant exchanges. A trunk-operator's table is thus located upon trunk-lines joining two or more central exchanges, and after an 70 operator has directed the switchmen at the two exchanges to connect two subscribers' lines, one to each end of a trunk-line, he joins the two fragments of the trunk-line at his own table, thus completing a circuit which then 75 includes the two subscribers' lines.

In the accompanying drawings, Figure 1 is a perspective view of the interior of my exchange, in which A C, A C', A C², A C³ are four sections of an annunciator-board having 80 as many annunciator-drops as there are subscribers' lines entering the exchange. An attendant is employed at each section of the annunciator-board. S B, S B', S B², S B³ are four sectional switch-boards, and a switchman 85 is assigned to each section, through which, say, two hundred and fifty subscribers' lines pass. T T and T T' are two trunk-line-operators' tables, and L T is a local-operator's table. Each of said tables is arranged for four 90 operators, who sit at its four sides, and each operator is provided with an entire and independent set of apparatus.

Fig. 2 is a diagrammatic view of an exchange showing sixteen annunciator-sections, 95 A C, tables T T for twenty trunk-operators, tables L T for four local operators, and eight switch-boards. The relative numbers of annunciator-attendants, switchmen, and operators may be somewhat varied, though I find 100 the foregoing the most advantageous.

Fig. 3 is a front view of a single section of the switch-board to which one switchman is assigned. Fig. 4 is a sectional view of a switch-board. Fig. 5 is a plan view of a 105 trunk-line table, showing four sets of apparatus, one for each operator seated at said table. Fig. 6 is an elevation view, partly in section, of one of the four-sided operator's tables. Fig. 7 shows one of the twenty circuit-connections from each trunk-operator's table to the several sections of the switch-board, and a trunk line to a distant exchange from the operator's table, also the telephonic connections from each trunk-operator to the several switchmen. Fig. 8 shows the various circuit-connections from a local-operator's table to the switch-board, also the line-connections through the switch-boards and annunciator to the earth.

As shown in Figs. 4, 7, and 8, a is a subscriber's line joining the fixed end of an electrical cord, b, upon which is hung a pulley-block supporting a weight, c. Cord b also passes over fixed pulleys d and d', and is 115 joined to the cylindrical shank p of a switch-plug, p². Said shank is provided with a metallic collar, p⁴, which normally rests upon a metallic ring-seat, p⁵, through which the cylindrical shank passes. Each ring-seat p⁵ is 120 electrically connected with an annunciator-drop, D², and the earth by a wire, p⁶. Each subscriber's line at the exchange is provided with an independent conducting-cord, b, and

annunciator-drop D². There are therefore as many cords b and weights c in an exchange as there are subscribers' lines entering the exchange. The earth connection of any subscriber's line through the annunciator-board is broken by the switchman by raising collar p⁴ from its seat p', and placing switch-plug p³ in a metallic socket or spring-jack, p². In its normal position collar p⁴ is firmly held upon its seat p' by cord b and weight c. To break the annunciator-connection of any line, the weight c is raised and switch-plug p³ is inserted in socket p²; and, again, when switch-plug p³ is removed from its socket p², weight c immediately draws shank p back into the ring-seat p' and re-establishes the earth connection through the annunciator.

As particularly shown in Fig. 3, the section of the switch-board S B is provided with two hundred and fifty switch-plugs, respectively, numbered from 1 to 250, all within the easy reach of a single switchman, and arranged in five rows upon the respective shelves P, P', P², P³, and P⁴. (See Figs. 1 and 4.) Immediately above the two hundred and fifty switch-plugs the central portion of the switch-board is provided with four hundred metallic sockets adapted to receive any one of the two hundred and fifty switch-plugs, which are arranged in twenty sub-sections or groups of twenty sockets each. Said sub-sections or groups are lettered, respectively, from E to X, and each sub-section corresponds with a trunk-operator's table, there being as many sub-sections as there are trunk-operators' tables. Each socket p² in the lettered sub-sections of the switch-board is independently connected by a wire, 5, Fig. 7, to the trunk-operator's table, and there are therefore twenty wires, 5, leading from a trunk-operator's table to the twenty metallic sockets, p², of the corresponding section of the switch-board. The socket—say 10—of section M on switch-board S B is electrically connected with socket 10, section M, of the other switch-boards, S B', S B'', &c., in the same exchange, and every socket of one sectional board is in the same manner electrically connected with a corresponding socket of all the others. Thus wire 5, leading from a trunk-operator's table, is connected to one socket upon each of the several sectional switch-boards, and said line 5 may be joined by the switchmen with any one of the subscribers' lines coming into the exchange. The upper portion of each sectional switch-board is provided with two hundred electrical sockets divided into four sub-sections or groups, A B C D, of fifty each, or twenty-five sets of two each. Sub-section A consists of the two upper rows numbered from 1 to 25; sub-section B the two upper rows from 26 to 50; sub-section C the two lower rows from 1 to 25, and sub-section D the two lower rows from 26 to 50. There are therefore fifty wires leading to each local-operator's table from the respective sockets of the sub-section of the sectional switch-board. Each pair of sockets is

arranged one above the other, Fig. 8, and to distinguish them from trunk-line sockets I designate them as p¹² and p¹³. Socket p¹² is connected by a wire, 12, to the local-operator's table, and p¹³ is connected to the local operator's table by a second wire, 13. Socket p¹² on one sectional switch-board is electrically connected with a corresponding socket on the other switch-boards; also socket p¹³ is connected to corresponding sockets of the other boards. By this means a subscriber's line coming into the exchange at switch-board S B may be plugged into connection with wire 12, while a subscriber's line coming into the exchange as at switch-board S B' may be plugged into connection at that board with wire 13, thus enabling any two subscribers' lines entering the exchange to be joined by the local operator at his table.

In Fig. 8 wire 13 is provided with an annunciator, D, and is connected to S J¹³, which forms one side of a spring-jack.

S J¹² is the opposite side of the spring-jack, to which is connected wire 12.

L S is a switch which normally connects wire 12 with the earth through contact L S'. A second fragment of wire, 12, is connected to contact L S², and when switch L S is thrown to the left the earth connection is broken and wires 12 and 13 are joined, thereby forming a loop through the local-operator's table from the switch-board.

For convenience of illustration, in Fig. 8 I have shown a head-telephone circuit, ht¹², with only a single spring-jack, S J¹⁴, at the local-operator's table, extending to the head-telephone H T of the switchman at switch-board S B, though in practice said circuit includes a spring-jack for every trunk and every local operator in an exchange, as is shown in the head-telephone circuit, ht, Fig. 1. Each local as well as each trunk operator has an independent spring-jack, S J¹⁴, and head-telephone circuit for each switch-board in the exchange, whereby the operator can call any switchman independently of the others. Each local and trunk operator is provided with a telephone-set consisting of a transmitting and receiving instrument embraced in a loop whose ends are respectively connected to the insulated portions q and q' of switch-plug Q. Said loop also includes two keys, K and K', which when depressed break the same, but when at back-contact maintain it closed. The switch-plug Q may be inserted in spring-jack S J¹⁴, to direct the switchman to make the required connections, and when so made the local operator may insert his switch-plug Q in spring-jack S J¹², S J¹³, with q in contact with S J¹² and q' in contact with S J¹³. When Q is thus inserted, the loop-circuit joining the two subscribers' lines will embrace the telephonic set T T' and keys K and K'. Upon depressing K the subscriber's line joined to line 12 at the switch-board will be connected to battery M B and the subscriber notified that the desired connec-

tion has been made. In the same manner K' is depressed to notify the subscriber whose line is joined to wire 13 at the switch-board. Each local operator is provided with twenty-five switches, L S, twenty-five spring-jacks, S J¹² S J¹³, twenty-five annunciators, D, and as many spring-jacks S J¹⁴ as there are switchboards or head-telephone circuits. The annunciator-cases are each provided with a telephone-set, Fig. 8, including a transmitter, T¹⁰, and a receiver, T⁹, a switch-plug, Q⁵, loop-wires 9 9, key K¹⁰, and a battery, M B⁹, one pole of which is connected to earth. Each subscriber's line at the annunciator passes through an ordinary spring-jack, thus enabling the annunciator-attendant to insert his switch-plug Q⁵ and converse with any subscriber whose line passes through his annunciator-board, or ring the subscriber's call-bell, by depressing key K¹⁰ and connecting the line with battery M B⁹.

As has already been stated, while wires in pairs connect the switch-board with the tables of local operators, only single wires connect the switch-boards with the tables of trunk-operators. The wire 5, Fig. 7, which connects corresponding sockets on the various switch-boards with a trunk-operator's table, is also connected to an anvil, s², with which switch s is normally in contact, and from which a circuit is completed to earth by wire 6, wire 7, annunciator D, spring-jack S J S J', wire 8, switch s', anvil s³, and wire 8. At the same time trunk link 6 is connected to earth by way of wire 7, annunciator D, and wires 7 and 8, and thereby annunciator-drop D at the trunk-operator's table may be operated either from the switch-board in the same exchange or from a distant exchange to which wire 6 is connected. Each switch-board has a battery, L B¹⁰, wire a¹⁰, weighted electrical cord b¹⁰, weight c¹⁰, fixed pulley d¹⁰, and switch-plug p¹⁰. Now, if the switchman desires to operate annunciator D either at a local or a trunk operator's table, he places plug p¹⁰ in the socket to which the wire connecting with said annunciator is joined, thereby closing a circuit through wire a¹⁰, wire 5, and wires 6, 7, and 8 to earth, Fig. 7, or through wires 13 and 12, Fig. 8. Annunciator D is also operated by depressing a key corresponding to K at the distant exchange.

The trunk-line operator is provided with a telephone-set, a switch-plug, Q, keys K K', and battery M B, precisely such as those of the local operators. Each side of a trunk-operator's table, T T, (see Figs. 5 and 6,) has twenty annunciators, D, a pair of keys, K K', twenty spring-jacks, S J S J', twenty pairs of double switches, S S', twenty sets of switch-anvils, s² s³ s⁴, and eight spring-jacks, S J², S J³, S J⁴, S J⁵, &c., though only four are here shown.

Figs. 7 and 1 show three spring-jacks, S J¹, S J², S J³, three circuits, h t h' h'', and three head-telephones, H T, H T', H T'', for the switchmen at switch-boards S B, S B', and S B''. These circuits show only one spring-jack in each,

though in practice, as before stated, and as is indicated in Fig. 1, each of said circuits is provided with as many springs-jacks as there are trunk and local operators.

The method of operation in this system is as follows: A subscriber desiring to communicate by telephone with another subscriber whose line is connected to the same exchange, calls by operating his annunciator-drop at the exchange, the annunciator attendant inserts his telephone in the subscriber's line and inquires what is wanted. Upon receiving an answer he writes two numbers upon a card, one indicating the subscriber who has called and the other the subscriber with whom the first desires to converse. The card is sent by a check-boy to one of the local operators. The local operator (see Fig. 8) inserts his switch-plug Q in spring-jack S J¹⁴ and directs the switchman to insert the main-line switch-plug p⁹ of the calling-subscriber's line into the lower metallic socket, say of 20^A, and if the other subscriber's line passes through the same switch-board the local operator also directs the same switchman to place the switch-plug of the second subscriber's line in the upper socket of 20^A. If, however, the line of the subscriber called passes through one of the other switch-boards instead, the operator must remove switch-plug Q from spring-jack S J¹⁴ and place it in the spring-jack of the other switchman's telephone-circuit. The operator will then direct the second switchman to place the switch-plug of the line of the subscriber who has been called for in the upper socket, 20^A, of his own switch-board. The line of the calling subscriber has now been disconnected from its normal earth contact and joined with wire 12, while the line of the second subscriber has also been disconnected from its normal earth and is connected to wire 13. The local operator then moves switch L S from anvil L S' to L S'', thereby breaking the earth connection of wire 13 and joining it to wire 12. The two subscribers now having been connected the local operator places switch-plug Q in spring-jack S J¹² S J¹³ and successively depresses keys K and K'. By depressing K' the call-bell of the subscriber with whom it is desired to communicate is operated, and by depressing key K a signal is also transmitted to the calling subscriber. The subscribers are thus notified that their lines have been connected. Switch-plug Q may remain in the spring-jack S J¹² S J¹³ during the conversation between the two subscribers, or it may be removed to be again employed in connecting other subscribers. If the switchman finds the line with which it is desired to connect busy, he places switch-plug p¹⁰, Fig. 7, in the socket 20^A, and thus actuates annunciator-drop D, which indicates to the local operator that the subscriber called for is engaged. The trunk-line operator receives notice of any desired connection either from the annunciator-attendant in the same exchange or from a trunk-line operator at an-

other exchange. If notified by card by the annunciator-attendant in the same exchange that a subscriber whose line enters the exchange desires to be connected with a subscriber whose line enters another exchange, the trunk-line operator first orders the switchman, who sits with a telephone to his ear, to connect the calling-subscriber's line with a certain line, as 5, Fig. 7, which connects the operator's table with the switch-board, thus joining the subscriber's line with the trunk-operator's table. The trunk-operator next inserts switch-plug Q in spring-jack S J S J' and rings an alarm or operates a drop at the distant exchange by depressing key K'. Further communication between the trunk-operators at the two exchanges is carried on by telephone. When the second subscriber's line at the distant exchange has been connected to the trunk-line, the trunk-operator moves switch-arm S from S² to S⁴, and S' is moved from S⁵ to S², thereby breaking the earth connection through wire 8 and joining wires 5 and 6 into a trunk-line between the two exchanges. Switch-plug Q still remains inserted in spring-jack S J S J' and keys K K' are alternately depressed, and the two subscribers are thereby notified that their lines are joined. Should the switchman find a line engaged with which he has been ordered by a trunk-operator to connect to the trunk-table, the switchman, instead of plugging the subscriber's line into connection with the trunk-table, will place his local switch-plug p¹⁰ in the same socket, and thereby actuate annunciator-drop D by the agency of battery L B¹⁰, the same as in the preceding case respecting the local table. A subscriber's line, when plugged into connection with an operator's table, is severed from its normal earth connection at the switch-board, and the circuit of the subscriber is only completed to earth at the operator's table. If all earth connection were broken at the exchange, the subscriber would be unable to transmit a call in case his line were by mistake plugged into connection with the table of an operator. To guard against such error a second switch, S, is employed, Fig. 7, whereby the wires 5 have a normal earth connection through annunciator-drop D. Thus should a switchman plug a subscriber's line into connection with an operator not expecting to be joined with such subscriber the operator would first be notified through his drop D of the accidental connection, and could immediately direct the switchman to correct his error. If wire 5 were left open at S², the subscriber would have no means for indicating that his line was opened and his call unanswered. It is obvious that two switches, S and S', as shown in Fig. 7, are not required at a local table, as in Fig. 8. In case of a local table, the calling operator is first joined to the upper wire, 13, and is thereby connected to earth through drop D. By this means the calling subscriber, if connected to the wrong operator by mistake of the switchman, may immediately there-

after be joined with the right one. The line of the second subscriber if not at first connected with the operator as directed by the latter another call from said operator will correct the error.

What I claim, and desire to secure by Letters Patent, is—

1. In a telephone-exchange, the combination of a series of subscribers' lines, a series of sectional switch-boards, and an annunciator-board through both of which said lines pass, and an operator's table which is in electrical communication with each of the series of sectional switch-boards.

2. In a telephone-exchange, the combination of an operator's table which is in communication with an annunciator-board from which directions for line-connections are sent, a series of sectional switch-boards to all of which directions are sent from each operator's table, switching devices for connecting the subscribers' lines with the operating-tables at the switch-board, and switching devices at the operating-table for joining the subscribers' lines together.

3. In a telephone-exchange, the combination of a series of subscribers' lines passing through each respective sectional switch-board, a series of sectional switch-boards, and an annunciator-board through which said lines pass to earth, an operator's table which is in communication with the annunciator-board and with each of the sectional switch-boards, switching devices for disconnecting the normal earth connections of the subscribers' lines and joining them to the operator's table, and switches for connecting the subscribers' lines together at the operator's table.

4. In a telephone-exchange, the combination, with a series of sectional switch-boards through which independent groups of subscribers' lines pass, annunciator calling devices independent of the switch-boards, an operator's table with which the subscribers' lines are connected by the switchmen at the direction of the operator, and switching devices for joining the lines together at the operator's table.

5. In a telephone-exchange, the combination of a series of sectional switch-boards through which the subscribers' lines pass, an operator's table to which the subscribers' lines are connected by the switchmen, and a telephone-circuit from the operator's table to each switchman.

6. In a telephone-exchange, the combination of a switch-board through which subscribers' lines pass, a series of wires joining the switch-board with an operator's table, a head-telephone for the switchman in a local circuit extending to the operator's table, and an operator's telephone in said circuit at the operator's table.

7. In a telephone-exchange, the combination of a series of sectional switch-boards through each of which subscribers' lines pass to earth, one or more pairs of wires joining

- each sectional switch-board and a local operator's table, one wire of each pair being normally open at the operator's table and the other connected to earth through an annunciator, and a switch for disconnecting the same from its earth connection and joining it to the normally-open wire, thus forming a loop from each sectional switch-board to and through the operator's table.
10. 8. In a telephone-exchange, the combination of a series of sectional switch-boards through each of which subscribers' lines pass to earth, one or more pairs of wires joining each sectional switch-board with a local operator's table, a switch for looping said wires together, a spring-jack in said loop, and a telephone-set, and a switch-plug for connecting the same in said loop.
9. In a telephone-exchange, the combination of a switch-board through which subscriber's lines pass to earth, a loop extending from the switch-board to an operator's table, a local circuit for the switchman's telephone, a spring-jack in the loop, and a spring-jack in the switchman's telephone-circuit at the operator's table, a telephone-set, and a switch-plug for joining said telephone either in the loop or in the switchman's telephone-circuit.
10. In a telephone-exchange, the combination of a series of sectional switch-boards through each of which subscribers' lines pass to earth, a trunk-operator's table, one or more wires joining each sectional switch-board with said operator's table through an annunciator-drop and to earth, one or more trunk-lines extending from the earth at the trunk-operator's table to a distant exchange, and a switch, both for disconnecting a wire from the switch-board and the trunk-line from earth at the operator's table and connecting them together.
11. In a telephone-exchange, the combination of a series of sectional switch-boards through each of which subscribers' lines pass to earth, one or more wires joining the switch-board with the trunk-operator's table, one or more trunk-lines joining said operator's table and a distant exchange, and a switch for joining one of the wires from the switch-board with a trunk-line at the operator's table.
12. In a telephone-exchange, the combination of a switch-board through which subscribers' lines pass to earth, a trunk-operator's table, a trunk-line and a spring-jack therein at the operator's table, a local telephone-circuit between the operator's table and the switchman, a spring-jack therein at the operator's table, a telephone-set, a switch-plug and signaling-keys K K', and battery M B, as and for the purpose described.
13. In a telephone-exchange, the combination of a series of sectional switch-boards through each of which subscribers' lines pass, an operator's table, a wire joining said operator's table and corresponding sockets upon the several switch-boards.
14. In a telephone-exchange, the combination of a series of sectional switch-boards through each of which subscribers' lines pass to earth, two wires, each of which connects corresponding sockets upon the several switch-boards and is then connected to a local operator's table.
15. In a telephone-exchange, a switch-board through which subscribers' lines pass, a series of conducting-cords and plugs which normally connect said lines to earth, a series of switch-plug sockets upon said board which are separately connected to operators' tables, the whole being so arranged that the cord-switch plugs may be removed from their normal positions and placed in said sockets, thus breaking the normal earth connections of the subscribers' lines and connecting the same with the operators' tables.
16. A sectional switch-board which is provided, first, with as many cord switch-plugs as there are subscribers' lines passing therethrough, and, second, with several sub-sections or groups of switch-plug sockets, the sockets of each sub-section being all independently connected with an operator's-table.
17. A sectional switch-board for a telephone-exchange, which is provided, first, with a series of cord switch-plugs; second, with several sub-sections or groups of switch-plug sockets, each sub-section being connected to a separate trunk-operator's table, and, third, with several sub-sections of switch-plug sockets, each sub-section in pairs being connected with a local operator's table, substantially as described.
18. In a telephone-exchange, the combination of several sectional switch-boards for a series of switchmen, a series of operators' tables, and a head-telephone for each switchman, placed in a local circuit leading to every operator's table in the exchange.
19. In a telephone-exchange, the combination of a series of sectional switch-boards each having corresponding sub-sections of switch-plug sockets, in which corresponding sockets of the same sub-section of the several sectional boards are connected together, and in which the several sockets of a sub-section are connected by independent wires with an operator's table, whereby each operator has several wires with which any switchman in the exchange may make connection.
20. In a telephone-exchange, the combination of a switch-plug and battery at the switch-board, a series of switch-plug sockets upon said board, to which wires are joined with operating-tables, and an annunciator for each such wire at the operator's table.
